United States Patent Office.

THOMAS HAZARD AND J. M. RICHARDSON, OF WILMINGTON, OHIO.

Letters Patent No. 61,830, dated February 5, 1867.

IMPROVED DOOR-STOPS.

The Schedule referred to in these Letters Patent and making part of the same.

TO WHOM IT MAY CONCERN:

Be it known that we, THOMAS HAZARD, and JONATHAN M. RICHARDSON, both of Wilmington, Clinton county, Ohio, have invented a new and useful Anti-Slammer; and we do hereby declare the following to be a full, clear, and exact description thereof, reference being had to the accompanying drawings making part of this specification.

This invention relates to a device adapted for ready insertion in the jamb or subbase of a door or the sill of a window, to soften the shocks and jars incident to their use.

Figure 1 is a perspective view of a door, whose jamb and subbase are furnished with the anti-slammer.

Figures 2 and 3 are axial sections, showing the two forms of our improvement.

A is a metallic case of cylindrical form, adapted to receive a pad or cushion B, of gum elastic or India rubber, and to be inserted in a circular hole or cavity prepared for it in the jamb or subbase of a door, or in the sill of a window. This cavity may be formed by means of an ordinary centre-bit, and should be of such size as to hold the case tightly, on the latter being simply driven into it. For additional security, the case may be dipped in glue or shellac just before insertion. A rim or flange C, around the external margin of the case, serves to strengthen the same so as to enable it to receive the blows of a mallet in the act of insertion, and also affords a bearing for the point of a pry or other instrument when its extraction may be desired. The rubber may be secured in its case either by the provision of a head or swell, D, at its inner end, which engages behind the corresponding end of the case, or by means of a shoulder, E, which bears against an offset, F, that projects internally from the case.

We are aware that India-rubber cushions have before been applied to door-stops in a variety of ways, and therefore do not claim the insertion of hollow or solid India rubber, or similar material, in holes bored in the door or jamb; but, by our invention, the rubber is protected by the metallic case, is easy of application for the purpose designed, and can be more readily removed when necessary; our invention, as herein described, being an improvement upon A. Eleiaer's patent "for Elastic Studs and Buttons for Doors and Windows, January 24, 1865."

We claim, and desire to secure by Letters Patent—

The combination of the case A C, and shouldered elongated cushion B, when constructed and adapted for use in the manner and for the purposes herein shown and described.

In testimony of which invention we hereunto set our hands.

THOS. HAZARD,
JONATHAN M. RICHARDSON.
